UNITED STATES PATENT OFFICE.

ROBERT M. JOHNSTON, OF MANSFIELD, OHIO, ASSIGNOR TO THE HUMPHREY MANUFACTURING COMPANY, OF MANSFIELD, OHIO, A CORPORATION OF OHIO.

COMPRESSED-AIR SPRAYING AND COATING MACHINE.

No. 921,409.

Specification of Letters Patent.

Patented May 11, 1909.

Application filed February 6, 1906. Serial No. 299,764.

To all whom it may concern:

Be it known that I, ROBERT M. JOHNSTON, a citizen of the United States of America, and a resident of the city of Mansfield, 5 Richland county, Ohio, have invented certain new and useful Improvements in Compressed - Air Spraying and Coating Machines, of which the following is a specification.

10 My invention relates to an apparatus for spraying, coating or applying paint, whitewash or other fluids and fine solids to surfaces by the force of compressed air.

One of the objects of my invention is to 15 combine a plurality of tanks or reservoirs with an air pump in such a manner as to permit the operation of the machine by one man.

A further feature of my invention is the 20 means employed of securing blades or paddles within and in close proximity to the bottom of the tank to agitate and commingle the fluid or liquid contained therein.

A further object is the application of 25 spring-actuated puppet valves to the air pump by means of which greater efficiency of air compression is obtained.

My invention comprises the following elements, a compound air pump, an air tank 30 and a liquid or fluid tank operated in conjunction with each other for the purpose of spraying and coating surfaces.

I attain these and other objects by the mechanism illustrated by the accompanying 35 drawing in which—

Figure 1 is a side elevation and plan view of the air and liquid tanks and air pump showing relative position of the paddle or bladed agitator in dotted line, also pipe connections and appliances. Fig. 2, is a diagrammatic sectional view of the air pump taken on the line X X of Fig. 1, showing the detail of the elongated plunger and arrangement of the puppet valves.

40 Similar characters of reference refer to similar parts throughout the several views.

In the construction of my device I provide a standard (1) shown in dotted lines. The base (2) of the air pump is formed 45 conical in shape with the end terminating in an outward extending annular flange which is secured to the base (1). The upper end (3) of the base is threaded to fit the outer periphery of the pump cylinder 50 (4) leaving the end resting on the partition

or wall (5). A similar partition or wall (6) is provided and spaced apart from the wall (5) forming an air chamber (7^a) communicating with the inlet air ducts (8). The outlet aperture (9) of the chamber is 55 screw-threaded interiorly to engage with one end of the pipes 10—10 with the opposite end connected to the air tank (11) thereby forming a passage or conduit from the chamber (7^b) of the pump. A globe 60 valve (b) is interposed between the air tank and pump and secured to the pipes 10—10 to prevent the air from flowing back into the chamber when the pump is not in use.

An aperture is provided in the upper wall 65 (5) having a tapered valve seat (12) surrounding said aperture and formed in the top of the wall. A similar tapered valve seat (13) surrounds a similar aperture formed in the wall (5) but is disposed on 70 the bottom of the wall. The seats (12) and (13) are formed on the wall on a plane with each other but disposed upon the top and bottom as shown. A valve (12^a) having 75 a stem (14) depending into the chamber 80 is fitted to contact with the seat (12).

The stem (14) is surrounded by a coil 85 spring (15) and held under compression by the collar (16) which forces the valve in contact with the seat. A valve (13^a) similar to the valve (12^a) is fitted to the valve seat with the stem (17) depending therefrom into the chamber alining with an aperture provided in the center of a circular standard (18) which is secured to the partition wall (6) directly underneath the valve seat (13). A coil spring (19) surrounds the valve stem (17), and is compressed between the collar formed by the valve and stem and the face of the standard exerting a tension 95 against the valve and forcing in contact with the seat (13). It will be observed that both valves are seated under spring tension. When the plunger (20) is reciprocated in the cylinder (4), the upstroke admits the 100 air into the cylinder and the suction of the plunger forces the valve (12) from its seat admitting the air freely into the cylinder from which it is forced by the plunger on the downstroke against the valve (13^a) forcing it out of contact with the seat (13) into the chamber and through the outlet pipes 10—10. The continuous reciprocation of the plunger in the cylinder charges the air tank with compressed air. The pressure is indi- 105

55 110

cated by the gage 21. The cut-off valve (22) prevents the air from flowing into the liquid tank until such time as it is desired to use it for the purpose intended.

5 The liquid tank (23) is of the ordinary construction. A paddle or bladed agitator (24) is mounted on a vertical shaft (25) which is journaled in the tee (26) with a stuffing box and adapted to be reciprocated or rotated by the 10 lever (27) for the purpose of agitating the liquid or fine solids to thoroughly commingle the liquid in the tank preparatory to spraying on surfaces of building or other bodies.

15 A globe valve (28) is secured to a pipe (29), a flexible hose (38) or other apparatus is inserted in the screw threaded free end of the valve to afford a means of controlling and shutting off the liquid flowing from the 20 tank under pressure. The lever (31) and link (32) are pivotally connected to the end (33) of the plunger and operate it in the usual manner. A hopper (34) and valve (35) are secured to the tee (36) to provide 25 means for filling the tank (23).

Having fully described my invention, what I claim and desire to secure by Letters Patent is—

In a spraying machine, the combination of a vapor compressor with a base having air 30 chambers located in the lower portion thereof and formed between partition walls, spring actuated puppet valves operating within said air chambers, a cylinder secured to said base, an elongated plunger fitted to 35 reciprocate within said cylinder, means to inject air into said chamber, means to force the air from said cylinder into air and liquid tanks, a vertical shaft projecting into and below the bottom of the liquid tanks, an 40 agitator located in the lower portion of the liquid tank and mounted upon said shaft, means to impart rotary motion to said agitator, an outlet pipe with a tee fitting secured to the lower portion of the liquid tank forming a journal support for said shaft, a flexible hose or other apparatus secured to the outlet pipe, means to reciprocate the plunger in the cylinder.

Signed at Mansfield, Ohio, this 3 day of 50 February 1906.

ROBERT M. JOHNSTON.
